ATTORNEY

UNITED STATES PATENT OFFICE

CHARLIE E. FRANKLIN, OF BURLINGTON, IOWA

GAME

Application filed August 9, 1929. Serial No. 384,708.

The game herein described is especially adapted to be played out of doors, but may also be played on a large table or floor where provision is made for placing a plurality of 5 series of balls in such position that the individuals taking part have sufficient space to roll, throw, or pitch a ring-like element from a somewhat distant point toward the balls, with a view to engaging or encircling one of 10 them at each play, if practicable, whereupon that ball is removed and the value assigned to it counted toward the score being made by each player, the highest score obtained during the game including say ten plays on each 15 side, determining the winner of the game.

With the foregoing and other objects in view, the invention consists in the novel construction and arrangement of elements disclosed, it being understood that modifications 20 may be made within the scope of the claim without departing from the spirit of the invention.

In the drawings forming part of this application:—

25 Figure 1 is a plan view showing the arrangement of the field, or of the board or table, in the event that the game is to be played indoors.

Figure 2 is a detail view showing five balls 30 representing one row of the various groups of Figure 1, the balls having applied thereto figures representing values to be counted in recording the score.

Figure 3 is a detail view representing a section of a field or the like in which are a plurality of holes or concavities adapted to receive balls with the numbered portions thereof turned downwardly, so that the player in 35 pitching the ring-like element merely takes the chance of engaging or enclosing the ball in a particular row having a relatively high number.

The dimensions of the field or board will 45 depend upon the circumstances, and especially whether the game is to be considered as an outdoor or an indoor game, both arrangements being practicable, and it is the intention that a plurality of alleyways will radiate 50 from a common center and at the outer end

of each alleyway an enclosure shall be provided constituting a player's position.

It is the intention further that each player's portion of the field or board shall be divided in accordance with a predetermined 55 plan.

In the drawings it will be observed that a plurality of alleyways, such as 10, 11, 12 and 13 radiate from a center at 14, and that the outer end portions of these alleyways each 60 have a player's position, base or plate, designated 15.

An enclosure in which the elements to be captured by each player are positioned includes a plurality of segmental portions 16, 65 arranged concentrically, these being defined in any suitable manner as by the use of lines on a board or by the use of suitable means applied to a field. Lines such as those designated 17 may radiate from the player's position 70 15, and a plurality of rows of concavities or holes will be located as illustrated, with reference to the segmental portions.

Although the arrangement of the concavities or holes 20 is not material, I have illustrated three rows, each including five concavities positioned in alignment. The concavities or holes 20 will receive balls 21 of suitable size, and adapted to receive numbers 22, the numbers defining values which 80 are to be placed upon the elements for scoring purposes.

It is obvious that the size of the balls, and the size of the elements to be rolled or thrown, will be determined by the size of the field or 85 board. For outdoor purposes, an annular element or elements of the approximate size of an automobile tire or say about thirty inches is suitable. Since in outdoor use the elements are to be rolled down the alleyways 90 from any player's position to an opposite position, automobile tires are themselves useful for the purpose. If desired a particular form of tire or ring of hard rubber of an inferior quality not suitable for other purposes 95 may be used, thus creating a market for this grade of material.

In playing the game, one player is expected to place the balls in position indiscriminately 100 with their numbered sides downwardly, and

the other player then proceeds from his position 15 to roll the ring-like element down the alleyway, or to throw a small element of this kind from position 15, and assuming that he is aiming at the balls in a given series, the element rolled or thrown will fall within the enclosure defined by the segmental portions, and will engage or enclose one or more of the balls.

10 These balls thus identified are removed for the time being and placed in racks as captured elements each having a particular value indicated by the number thereon, and the totals after making ten plays on each side, 15 will indicate the winner of the game, or the person scoring the highest number of points.

What is claimed is:—

A game including a center portion, alley-ways radiating from said center portion, a 20 base on which a player stands when playing, located at the outer end of each alley-way, semi-circular fields located at the outer ends of the alley-ways and divided into segments radiating from the respective bases and having 25 a plurality of sockets arranged in rows radiating from the bases, indicia bearing elements located in said sockets with the indicia hid within the sockets, said elements adapted to be removed when engaged or encircled by 30 a playing element thrown by a player standing on the base located diametrically opposite to the respective field.

In testimony whereof I affix my signature.

CHARLIE E. FRANKLIN.
